UNITED STATES PATENT OFFICE.

JOHN TOWERS, OF FARGO, NORTH DAKOTA.

GRAIN-CAR-DOOR-OPERATING MEANS.

Application filed May 11, 1927. Serial No. 190,627.

This invention relates to grain car door operating means.

It has been found that, due to the tremendous pressure exerted on the doors of a grain car, by the grain within the car, it is with considerable difficulty that the doors are opened to allow the grain to pass out through the door openings.

It is therefore one of the objects of the present invention, to provide improved means which facilitates the unloading of a car laden with grain, by partly overcoming the effect of the tremendous pressure exerted on the doors of the car by the grain.

Another and more specific object of the invention is to provide means for the purpose stated, which functions in conjunction with a pivotally mounted door, to apply to such door, a sufficient force, in a quick and easy manner, to move the door against the pressure exerted thereon, to the end that the door will be moved from its closed to a partly opened position.

The nature of the invention and its distinguishing features and advantages will appear when the following specification is read in connection with the accompanying drawing, in which—

Figure 1 is a side elevation of the central portion of a grain car showing one of the doors in its closed position.

Fig. 2 is a sectional view taken on the line 2—2 of Fig. 3, the door being shown in its opened position.

Fig. 3 is a transverse sectional view taken on the line 3—3 of Fig. 1, and illustrating the manner in which the door is moved to a partly opened position.

Fig. 4 is a sectional view through one side of the car, the section being taken on the line 4—4 of Fig. 1.

Figs. 5 and 6 illustrate the bar used for moving the doors.

The present invention involves the combination of a railroad grain car 10, doors 11 and means for operating the doors 11.

The grain car 10 includes sides 12 each having a door opening 13. The floor of the car is indicated at 14. Each of the door openings 13 is controlled by one of the doors 11 and is mounted for movement to opened and closed position with respect thereto. Each door has a pivot 15 on one of the lower corners thereof which extends through the side 12 adjacent the door opening. A suitable block 16 serves to provide

adequate bearing surface for the pivot 15. In this way the door 11 is mounted for pivotal movement to control the door opening 13.

In order to effect the pivotal movement of the door, the pivot 15 has connected therewith a socket 17 which is disposed exteriorly. The opening 18 in the socket 17 is somewhat elongated for a purpose to appear. A bar 19 is provided. The bar 19 has a socket engaging portion 20 at one end. The portion 20, cross sectionally, is of the same shape, and substantially of the same size as the opening 18. It will therefore be understood that it is necessary to insert the portion 20 in the opening 18 of the socket 17 in such a manner that the bar 19 will be properly disposed for a lifting action to open the door, also for exerting a pulling force thereon when the door is in an open position, to move the door to a closed position. The portion 20 also has a notch 21 for a purpose to appear hereinafter.

In order to hold each door 11 in a closed position and to prevent rattling, there are provided hooks or the like 22 respectively at opposite sides of the door opening. Each hook 22 is pivoted as at 23 to a portion of the door frame. These hooks 22 are adapted to be swung over the upper edge of the door which will prevent upward movement, also vibration of the door. The hooks 22 may be disengaged to allow the door to be moved when that is desired. These hooks may serve to hold the door in a closed position when the car is empty, and it is desired to have the door at each side of the car closed. When each door is swung to its open position, it engages a stop 24 secured to the side 12. The said stop 24 includes a buffer 25 of suitable material, such as rubber, and a portion 26 which sets up a wedging action on the edge of the door. The stop 24 prevents the door from touching the floor 14, and prevents the door from being dislodged by jarring when the car is in motion.

It has been found that due to the tremendous pressure exerted on the doors of a grain car when loaded, that it is almost impossible to move the doors to allow the grain to pass out through the door openings. A capacity load of grain weighs about eighty thousand pounds, which exerts a tremendous pressure on the doors. In order to overcome the effect of this pressure on each door there is provided a means, which may be operated by a suitable lever. The said means

acts against the lower edge of each door 11. In the present instance, the means includes a member 27 which is guided for up and down movement through an opening 28 in the floor 14 and an opening a plate 29 secured to one of the longitudinals of the car. The upper end of the member 27 has an angular portion or head 30 which acts on the lower edge of the door, and is also engageable with a portion of the floor 14 to limit the downward movement of the member 27. A stop 31 carried by the member 27 is engageable with the plate 29 and also performs with the head 30 in limiting the downward movement of the member 27, and also limits the upward movement of the said member 27. When each member 27 is in its normal position the lower end 32 will project some distance below the plate 29 as shown in Figs. 1, 2 and 3. Each member 27 will be moved with the bar 19 which serves with a fulcrum element 33 fixedly secured as at 34 to a portion of the car, adjacent the member 27. The bar 19 and element 33 constitute a lever, which serves for the application of considerable force to the member 27 to raise the latter, thereby lifting the door 11 associated therewith. To accomplish this end, the lower end 32 of the member 27 is engaged in the notch 21 in the portion 20 of the bar 19, as illustrated in Fig. 3. By bearing down on the outer end of the bar 19 the door 11 may be moved to a partly open position. This will allow the grain within the car to pass out between the lower edge of the door and the floor. In time, pressure on the door will be reduced to such an extent that the door may be moved to its fully open position. This is accomplished by inserting the portion 20 of the bar 19 in the opening 18 of the socket 17, whereupon the bar 19 may be swung upwardly causing the door to move on its pivot 15 to the open position in engagement with the stop 24. The contents of the car may then be removed.

From the foregoing it will be apparent that provision is made for overcoming or relieving pressure on the doors of a grain car to subsequently allow the doors to be moved to fully opened positions; that the means provided for carrying out this result is extremely simple and practical, and one which may be operated by one man; and that by virtue of the provision of such means the unloading of grain cars will be greatly facilitated.

I claim:

1. The combination with a grain door having a door opening; of a door controlling said opening, a member guided for upward movement so as to act on said door, and separate means for effecting the upward move-

ment of said member to apply a lifting force to said door to move the door to a partly open position.

2. The combination with a grain door having a door opening; of a pivotally mounted door controlling said opening, a member guided for movement so as to act on said door, separate means for effecting the movement of said member to cause the latter to act on said door at a point remote from its pivot to move the door to a partly open position, and means limiting the movement of said member.

3. The combination with a grain car having a door opening; of a door controlling said opening, a member guided for movement so as to act on said door, a fulcrum on the car, and a separate bar adapted to coact with the fulcrum and said member, to move said member to cause the latter to act on the door to move the door to a partly open position.

4. The combination with a grain car having a door opening and a floor; of a door for controlling said opening, means including a pivot mounting the door for pivotal movement; a socket connected with the pivot, means including a separate bar serving for the purpose of imparting initial pivotal movement to the door up from the floor to a partly open position, and said bar adapted to cooperate with said socket to effect the pivotal movement of the door to its fully opened position and to its closed position.

5. The combination with a grain car having a door opening; of a door controlling said opening, a member guided for upward movement so as to act on the lower edge of said door, a fulcrum fixedly mounted below said member, and a separate bar adapted to coact with the fulcrum and said member to move said member upwardly to apply a lifting force to the door to move the door to a partly open position.

6. The combination with a car having a door and a floor on which the door rests when in a closed position; of means including a pivot mounting the door for pivotal movement to opened and closed positions, a socket connected with the pivot, a member guided for upward movement so as to act on the lower edge of the door at a point remote from its pivot, a fulcrum fixed in position below said member, and a separate bar adapted to be used in conjunction with said member and said fulcrum to enable a person to move said member upwardly to apply a lifting force to the door to move the door to a partly open position, and said bar also adapted to fit in said socket to enable a person to effect the pivotal movement of the door to a fully opened position.

JOHN TOWERS.
